JAN ROOTHAAN, OF HAYES, ENGLAND.

COIL FOR ELECTRICAL TRANSFORMERS.

Application filed February 8, 1922. Serial No. 534,888.

To all whom it may concern:

Be it known that I, JAN ROOTHAAN, a subject of the Queen of the Netherlands, residing at Hayes, Middlesex, England, have 5 invented Improvements in or Relating to Coils for Electrical Transformers, of which the following is a specification.

This invention relates to improvements in the construction of coils for electrical transformers, particularly those designed to be used in high voltage transformers.

The solid insulation material used between the turns of a transformer coil or winding, usually consists of a composite material, the basis of which is cotton, flax, paper silk or like fibrous material, impregnated or treated with varnish, oils and the like. Such material as a rule is more or less hygroscopic, shrinks when in use, is a bad conductor of heat and is easily damaged by abrasion and otherwise. Moreover, when several layers of such material are wound between and over the turns of conductor, the insulation cannot be considered homogeneous; and owing to the composite nature of such material being of varying specific inductive capacities, the dielectric strength of such insulation is more or less an unknown quantity.

30 The object of the present invention is to use for the insulation of transformer coils apart from the oil in which the transformer may be immersed when in use, solid insulating material free from the objectional features above referred to.

For this purpose, there is used according to the present invention, for insulating the turns of the conductor forming a transformer coil, homogeneous insulating material of the kind commercially known as bakelite, formite, formalite and the like or of pure mica which is practically non-hygroscopic, heat resisting, mechanically strong, very refractory; does not warp or shrink and is an excellent insulator. Of such insulation materials, it is preferred to use one having the same or substantially the same specific inductive capacity as the oil in which the transformer embodying such a coil is immersed when in use.

In the construction of a transformer coil embodying such insulation material, according to the present invention, the coil is formed of bare conductor of circular, rectangular or other suitable cross section, the

turns of which are mainly insulated from each other by air during the construction of the coil and afterwards by the oil in which the transformer containing the coil may be immersed when in use, solid insulation material being used in the form of suitably shaped separators, binders and distance pieces, for holding the turns together and taking up mechanical stresses. The separators, binders and distance pieces should, in order to obtain the best results, be shaped in such a manner as to conform with the lines of force of the electrostatic field produced adjacent thereto when the coil is in use.

A transformer coil thus constructed possesses many practical advantages. Thus, when the coil is in use, not only the oil in which it is submerged can be considered as homogeneous (which is very important from an insulating point of view), but also, the solid insulating material used as separators, binders and distance pieces. The latter material is not liable to absorb moisture. Due to this and to the fact that when the solid insulation material has a different specific inductive capacity to that of the oil, the separators, binders and distance pieces can be shaped so as to conform to the lines of force of the electrostatic field adjacent thereto, so that the break-down voltage between adjacent turns of conductor or between the conductor and nearest earth, can be accurately determined, which is not possible with the usual methods of insulation involving the use of fibrous material.

The cooling of the coil also is excellent. If due to outside disturbances, the oil insulation between any neighbouring turns of conductor be pierced, the oil insulation will immediately be restored whereas with the usual method of insulation, the damage is permanent. Also, the grading of the insulation of reinforced coils can be made theoretically correct and there is no shrinkage of the solid insulation material used. Furthermore, no moisture can be absorbed by the insulating material when the transformer is taken out of the oil tank. Consequently, drying out, a very important and difficult matter with transformer coils having any fibrous insulation, is reduced to a very simple and easily carried operation.

Transformer coils embodying the invention can be constructed in various ways to obtain the advantages of the invention.

In the accompanying illustrative drawings, Fig. 1 shows in side elevation, Fig. 2 in cross section on the line 2-2 of Fig. 1 and Fig. 3 in plan, part of a transformer coil, according to the invention and how it is constructed, the coil being shown on a former. Figs. 4 to 7 are detail views, Figs. 4 and 4^a being respectively a side view and end view of a radial separator, Figs. 5 and 5^a a face view and edge view respectively of a distance piece, Figs. 6 and 6^a views at right angles to one another of a radial binder; and Figs. 7 and 7^a a face and edge view respectively of connecting means between the adjacent ends of two coils of conductor. Figs. 8, 9 and 10 are respectively a side elevation, plan and cross section of part of a former for use in building up coils according to the invention. Figs. 11 and 12 are respectively a plan and side elevation of part of a modified construction of coil. Fig. 13 is a detail view of two adjacent radial binders. Fig. 14 shows in cross section, part of a modified construction of coil. Figs. 15 and 16 show respectively in plan and cross section, part of a still further modified construction of coil, whilst Fig. 17 shows separately, one of the insulating distance pieces used therein.

In the construction of transformer coil shown in Figs. 1, 2 and 3, there are two sets *a* and *b* of turns or convolutions (hereinafter called convolutions) formed of bare strip copper, arranged in parallel planes and separated from each other laterally by a number of suitably spaced radial separators *c* (Figs. 4 and 4^a) formed of solid insulating material of the kind herein referred to, for example bakelite or formalite, each such separator being in the form of a rod of square or rectangular cross section and having a head *c*¹ at its inner end adjacent to the inner periphery of the two sets *a* and *b* of convolutions. Between the successive convolutions of copper strip in each set *a* and *b* thereof, and in proximity to the radial separators *c*, are distance pieces *d* (Figs. 5 and 5^a) consisting of flat rectangular pieces of insulating material of the kind referred to. At the outer sides of each of the two sets of convolutions *a* and *b* are a number of radial binders *e* (Figs. 6 and 6^a) formed of insulating material of the kind referred to, arranged, it may be, and as shown, in the same transverse planes as the radial separators *c* and each provided at its inner and outer ends with laterally extending projections or lugs *e*¹, *e*² respectively adapted to be forced over the complete set *a* or *b* of convolutions of strip conductor constituting the adjacent coil so as to bind the turns of conductor and interposed distance pieces *d* firmly together. Each binder *e* may be of square or rectangular shape in cross section. Each

of the flat distance pieces *d* may extend laterally, as shown, beyond the edges of the copper convolutions and be formed at two of its opposite edges with square or rectangular shaped notches *d*¹ to fit the adjacent radial separator *c* and binder *e* and thereby be held securely in position. The end portions *a*¹ and *b*¹ (Fig. 7) of the two sets of convolutions *a* and *b* constituting a pair of coils are suitably formed to enable them to be connected together in series to form a unit and to adjacent sets of similarly constructed coils forming adjacent units. Such connection may be effected by the aid of a short strip of copper *f* (Figs. 7 and 7^a) riveted to the adjacent ends of the coiled strips and having a transversely arranged expansion bend *f*¹ therein.

For constructing such a pair of coils, there may advantageously be used a former (Figs. 2, 8, 9 and 10) consisting of a central hub composed of two metal rings *g*, *g*¹ arranged side by side and detachably connected together, as by set screws *h*, and a series of U shaped metal guide bars *i* secured to the outer sides of the hub, as by set screws *j*. The combined rings are formed at the outer periphery and at their inner sides with recesses *k* to form slots in which the inner enlarged ends *c*² of the radial separators *c* can be clamped in position. The rings *g*, *g*¹ are also provided, on their outer periphery, with slots *m* in which the inner ends of the copper strips can, after being connected together by a strip of copper, as shown in Figs. 7, 7^a, be fixed preparatory to winding the strips into coil form which is done by winding them between the U shaped guide bars *i* and the radial separators *c* (Figs. 1 and 2), the flat distance pieces *d* being placed in position as the winding proceeds. When the winding is finished, the binders *e* are forced into place laterally to hold the two sets *a* and *b* of convolutions of conductor firmly together. The two rings *g*, *g*¹ with guide bars *i* are then separated from each other and the complete set of coils removed.

In the modified construction shown in Figs. 11 and 12, the convolutions of bare conductor in each set *a* and *b* thereof are separated at intervals by flat distance pieces *d* of insulating material of the kind referred to, formed at one side only with a notch *d*¹ of dove tail shape through which extends a radial separator *c* of corresponding shape in cross section. In such a case the distance pieces *d* may, as shown, extend beyond one side only of the corresponding set of convolutions and the corresponding radial separators *c* may, as shown, extend slightly beyond the distance pieces so as to bear against an adjacent set of convolutions.

When two or more such pairs of coils *a* and *b* are to be assembled sideways of one

another, the binders *e* on one side of one pair of coils may each be formed with a radial rib *e*³, as shown in Fig. 13, and those on the other side be each formed with a corresponding radial recess *e*⁴, so that the ribs on the binders on one side of one set or pair of coils *a* and *b* can enter recesses in the binders of an adjacent set or pair of coils, for the purpose of easily positioning the sets of coils.

The edges of the copper strips may be of curved shape, as also may be the edges of the distant pieces, radial separators and binders for the purpose hereinbefore mentioned.

In the construction of the double coil shown in Fig. 14, the adjacent convolutions of each of the coils *a* and *b* formed of copper strips having rounded edges, are separated by distance pieces *d* of insulating material recessed on each side to fit the adjacent sides and edges of the convolutions of conductor and having rounded edges extending from the edges of the convolutions so as to provide for uniform electro-static fields between the turns at all parts thereof. The radial separators *c* between adjacent coils *a* and *b* and the binders *e* may be shaped to fit the rounded edge portions of the convolutions and distance pieces *d* or not as may be desired. The said parts are shown as fitting one another.

In the case of coils formed of convolutions of copper conductor of circular section, as shown in Figs. 15, 16 and 17, the distance pieces *d* may, as shown, have rounded inner and outer edges *d*² with intermediate oppositely arranged concave recesses *d*⁵ to receive the convolutions of conductor. In this case the radial separators *c* are displaced angularly with reference to the distance pieces *d* and may be formed on opposite sides with concave recesses *c*³ to receive the convolutions of adjacent coils. The binders, not shown, may also be similarly recessed on one side to receive the turns of the adjacent coil.

The details of construction of electrical transformers embodying the invention, can be variously modified.

What I claim is:—

1. A transformer coil comprising adjacent sets of convolutions of bare conductor, radial separators adapted to space the sets of convolutions apart, distance pieces, each consisting of a small plate, interposed between successive convolutions of the same set to space them apart, and radial binders applied to each set of convolutions after the winding thereof is completed, the separators, distance pieces and binders being separate members all formed of homogeneous insulating material and being arranged at intervals around the convolutions of conductor in such a manner that the convolutions are

mainly insulated from each other by air previous to immersion in oil.

2. A transformer coil comprising adjacent sets of convolutions of bare conductor, radial separators adapted to space the sets of convolutions apart, distance pieces, each consisting of a small plate, interposed between successive convolutions of the same set to space them apart, one edge of each distance piece extending laterally beyond the edge of the convolutions, the said edge of the distance piece being so shaped as to be adapted to interlock with a radial separator, and radial binders applied to each set of convolutions after the winding thereof is completed, the separators, distance pieces and binders being separate members all formed of homogeneous insulating material and being arranged at intervals around the convolutions of conductor in such a manner that the convolutions are mainly insulated from each other by air previous to immersion in oil.

3. A transformer coil comprising adjacent sets of convolutions of bare conductor, radial separators adapted to space the sets of convolutions apart, distance pieces, each consisting of a small plate, interposed between successive convolutions of the same set to space them apart, one edge of each distance piece extending laterally beyond the edge of the convolutions, and radial binders applied to each set of convolutions after the winding thereof is completed, the protruding edge of each distance piece being so shaped as to be adapted to interlock with an adjacent radial binder, the separators, distance pieces and binders being separate members all formed of homogeneous insulating material and being arranged at intervals around the convolutions of conductor in such a manner that the convolutions are mainly insulated from each other by air previous to immersion in oil.

4. A transformer coil comprising adjacent sets of convolutions of bare conductor, radial separators adapted to space the sets of convolutions apart, distance pieces, each consisting of a small plate interposed between successive convolutions of the same set to space them apart, and radial binders applied to each set of convolutions after the winding thereof is completed, the distance pieces between adjacent convolutions of bare conductor being recessed at opposite sides to form recesses for the reception of the convolutions, and the separators, distance pieces and binders being separate members all formed of homogeneous insulating material and being arranged at intervals around the convolutions of conductor in such a manner that the convolutions are mainly insulated from each other by air previous to immersion in oil.

5. A transformer coil comprising adja-

4
5 cent sets of convolutions of bare conductor spaced apart by radial separators, the convolutions in each set being spaced apart by interposed distance pieces and held together by radial binders, the separators, distance pieces and binders being formed of homogeneous insulating material arranged at intervals around the convolutions of conductor in such a manner that the convolutions are 10 mainly insulated from one another by air previous to immersion in oil, and the edges of the bare conductor forming the sets of convolutions and the adjacent edge portions of the distance pieces, separators and binders 15 being shaped to conform with the lines of force of the electrostatic field set up when the coil is in use.

6. A transformer coil constructed according to claim 1, the binders at opposite sides 20 of a coil having two sets of convolutions of the conductor adapted to interlock with the binders of one or more adjacent similarly

constructed coils, substantially as described for the purpose specified.

7. A transformer coil comprising two annular sets of convolutions of bare copper arranged side by side and connected together in series, short distance pieces arranged at intervals between the convolutions of each set of convolutions, spaced separators between the two sets of convolutions and spaced binders at the outer sides of the connected sets of convolutions, each binder being adapted at its ends to clamp the corresponding set of convolutions and interposed distance pieces firmly together, the distance pieces, radial separators, and binders being formed of hard, solid non-absorbent insulating material and the separators and binders being interlocked with the distance pieces, the whole forming a unit coil.

Signed at London, England, this 20th day of January, 1922.

JAN ROOTHAAN.
